J. L. KING

SAFETY RAZOR

Filed Dec. 6, 1924

Ch. Parker
Attorney

UNITED STATES PATENT OFFICE.

JOHN L. KING, OF BALTIMORE, MARYLAND.

SAFETY RAZOR.

Application filed December 6, 1924. Serial No. 754,401.

This invention relates to safety razors and more particularly to such a device employing a blade adapted to be reciprocated in a line parallel to its cutting edge to provide a 5 shearing cut.

An important object of the invention is to provide a device of the above mentioned character having novel means for reciprocating the blade whereby the latter is adapted 10 to cut with a shearing motion.

A further object of the invention is to provide a roller adapted to contact with the skin to be revolved thereby to impart a shearing action to the blade, novel means being 15 provided for rotatably supporting the roller.

A further object of the invention is to provide means for regulating the cut of the blade by means of a guard adjustable toward and away from the cutting edge of the 20 blade.

Other objects and advantages of the invention will be apparent during the course of the following description.

In the drawings I have shown several embodiments of the invention. In this showing,

Figure 1 is a front elevation of the device,
Figure 2 is a side elevation,

Figure 3 is an enlarged side elevation of 30 the frame and associated elements,

Figure 4 is a plan view of the device open with the blade removed,

Figure 5 is a section taken on line 5—5 of 35 Figure 1,

Figure 6 is a detail perspective of the blade and operating lever therefor,

Figure 7 is a detail perspective of a portion of the frame and associated elements,

Figure 8 is a detail perspective of the 40 guard, and

Figure 9 is a detail perspective of a modified form of guard.

Referring to the drawings the numeral 10 designates a frame as a whole which is generally rectangular in shape and is provided with a rearward extension 11 having a depressed internally screw-threaded portion 12. A handle 13 has a portion adjacent its upper end threaded as at 14 for reception 45 within the screw-threaded opening in the frame as will be obvious. The handle 13 is provided at its upper end with a substantially axial extension 15 preferably formed

as a screw driver for a purpose to be described.

The frame 10 is provided adjacent its rear edge with preferably integral upstanding arms 16 each of which is provided with a rearwardly opening slot 17.

A roller 18 is arranged between the arms 16 as clearly shown. The roller 18 is preferably corrugated to form an efficient rolling contact with the skin of the user and each end of the roller is provided with an axial stub

shaft 19 adapted to be arranged in the slot 65 17 and corresponding in diameter thereto.

The roller 18 is provided preferably centrally thereof with a serpentine groove 20. An operating lever 21 is pivotally connected as at 22 with the rearward extension 11 of 70 the frame and is provided intermediate its ends with a pin 23 upstanding therefrom and arranged within the groove 20. The forward end 24 of the lever 21 is adapted

to engage a razor blade to impart a reciprocating motion thereto in a manner to be described.

The upper face 25 of the frame 10 is provided with small upstanding knobs 26 upon which the blade is adapted to rest as will 80 become obvious. The central portions 27

of the frame 10 are depressed between the projections 26 as clearly shown in Figures 4 and 5. A pair of elongated aligned projections 28 are arranged on the frame 10 85 near opposite edges of the upper face thereof as clearly shown in Figure 4. The numeral 29 designates a razor blade having a forward cutting edge 30. The rear edge of the blade is provided with a cutout portion 31 90 in which the forward end 24 of the lever is adapted to be arranged when the blade is in position. The blade is adapted to be

arranged on the upper face of the frame 10 and is provided in opposite ends with slots 95 32 adapted to receive the elongated depressions 28. When the blade is in position it will be obvious that it is adapted to be supported by the projections 26.

A retaining clamp 33 is adapted to engage 100 the upper face of the razor blade to maintain it in position. The retaining member is provided at its rear edge with arms 34 having forwardly opening slots 35 therein. These slots are equal in width to the diameter 105 of the stub shafts 19 and are adapted

to receive the shafts therein. The lower face of the retaining member 33 is provided with projections 36 adapted to contact with the upper face of the razor blade. It will be obvious that the blade is engaged on opposite sides by the projections 26 and 36 and is adapted to slide therebetween. The retaining member 33 is further provided with a central lug 37 which is adapted to be arranged in the central slot 38 in the razor blade. As shown in Figure 4, the retaining member 33 is provided in opposite ends with cutout portions 37' adapted to receive the projections 28 when the retaining member 15 is in closed position. Lips 39 extend from opposite ends of the retaining member to facilitate the opening thereof when it is desired to remove or replace the blade.

Referring to Figures 3 and 7, the numeral 20 39 designates as a whole a resilient member having its forward end arranged beneath the frame 10 and adapted to be secured thereto by screws 40 or the like. The member 39 is provided adjacent each end of its rear 25 edge with a pair of resilient arms 41 and 42. Each of the arms 42 is adapted to engage a cam 43 projecting rearwardly from the retaining member 33. It will be obvious that the spring 42 is adapted to hold the 30 retaining member in engagement with the blade when the device is in position shown in Figure 3 and is adapted to engage the forward portions of the arms 34 to hold the retaining member in open position when it 35 is desired to remove or replace the blades. Each of the arms 41 is arranged adjacent one of the slots 17 formed in the arms 16.

The frame 10 is provided adjacent each forward corner with an apertured arm 44 40 as clearly shown in Figures 1 and 7. A guard roller 45 is arranged between the arms 44 and one end of the roller is provided with a longitudinally extending eccentric pin adapted to be arranged in the 45 opening in one of the arms 44. The opposite end of the roller is provided with an eccentric opening 47 arranged in alignment with the pin 46. A screw 48 is adapted to be arranged in the opening in the opposite 50 arm 44 and to engage in the opening 47. In Figure 8 of the drawings, I have shown a substantially cylindrical guard but the latter need not be circular in cross section. In Figure 9 I have illustrated a modified form 55 of guard. As shown I provide in this form a guard 49 which is substantially triangular in cross section and is also provided with an eccentric pin 50 adapted to be arranged in the opening in one of the arms 44. The 60 opposite end of the guard 49 is provided with an opening (not shown) similar to the opening 47 to receive the pin 48.

The operation of the device is as follows:

The blade is arranged in position on the 65 frame with the projections 28 engaging the

slots 32. The retaining member 33 is then closed with the pin 37 engaging in the central slot 38. If desired the guard may be adjusted according to the closeness of the shave desired by individual users. The handle may be unscrewed from the frame and the screw driver end 15 thereof employed for loosening the screw 48. The guard then may be revolved to any desired position and the screw 48 tightened. The handle is then replaced in position as shown in Figure 5. When in use the razor is moved in contact with the skin in the usual manner and the engagement of the roller 18 against the skin causes the latter to revolve. The engagement of the pin 23 in the serpentine groove 20 causes the forward end 24 of the lever 21 to oscillate. Since the forward end of the lever is engaged in the slot or cutout portion 31 it will be obvious that the blade will be reciprocated in a line parallel to its cutting edge thus causing a shearing action of the blade. The central portion of the frame is depressed to prevent any binding action between the blade and frame if the former becomes warped or bent in any manner. The projections 26 and 36 are adapted to support the blade and these projections are preferably provided with smooth polished faces to reduce the friction between the projections and the blade so that the latter may reciprocate freely.

With the construction shown and described it has been found that the various structural elements may be easily and quickly assembled and disassembled. In assembling the device the roller 18 is first arranged with the stub shafts 19 above and between the arms 16 and springs 41. The roller is then pressed downwardly forcing the springs 41 outwardly until the stub shafts slide into the open ends of the slots 17. The retaining member 33 is then arranged with the slot 35 projecting in substantially the opposite direction to that shown in Figure 3 and is then moved rearwardly to place the stub shaft 19 within the slot 35. With the stub shafts in the deeper portions of the slots 35, the retaining member is then swung over to the position shown in Figure 3, the cam portions 43 forcing the springs 42 rearwardly to permit the swinging movement of the retaining member. It will be obvious that the pressure in the springs 42 projects the retaining member forwardly so that the shaft 19 will be arranged in the deeper portions of the slots 35 and this forward pressure also maintains the shaft 19 in the deeper portions of the grooves 17. Thus it will be seen that the stub shafts will be securely held in position and yet permitted to revolve freely.

It is to be understood that the forms of my invention herewith shown and described are to be taken as preferred examples of

the same and that various changes in the shape, size and arrangement of parts may be resorted to without departing from the spirit of the invention or the scope of the 5 subjoined claims.

Having described my invention, I claim:

1. A safety razor comprising a frame having a pair of arms provided with alined slots, a roller mounted between said arms 10 and provided at its ends with stub shafts arranged in said slots, means for retaining said stub shafts in said slots, a blade arranged on said frame, and means connected between said roller and said blade for reciprocating the latter in a line parallel to its cutting edge when said roller is revolved.

2. A device constructed in accordance with claim 1 wherein said retaining means for the stub shafts comprises springs carried by said frame and having free ends arranged adjacent the open ends of said slots.

3. A safety razor comprising a frame provided adjacent its rear edge with a pair of 25 spaced upstanding arms having alined slots therein, a roller mounted between said arms and provided with axial stub shafts projecting through said slots, a retaining member arranged over said frame and provided 30 with arms having apertures receiving said stub shafts, a blade arranged between said frame and said retaining member, connections between said roller and said blade for reciprocating the latter in a line parallel to 35 its cutting edge when said roller is revolved, and resilient means engaging said retaining member and adapted to maintain said stub shafts in said slots.

4. A device constructed in accordance 40 with claim 3 wherein said resilient means comprises a spring carried by said frame and having portions engaging against the arms of said retaining member opposite the open ends of said slot.

45 5. A safety razor comprising a frame having a pair of spaced upstanding arms adjacent its rear edge provided with open ended slots, a member arranged between said arms and provided with stub shafts 50 projecting through said slots, a blade arranged on said frame, a retaining member normally arranged over said blade, said retaining member having upstanding arms arranged adjacent the arms of said frame and 55 provided with open ended slots extending in a different direction from said first named slots and receiving portions of said stub shafts, and means carried by said frame and engaging said retaining member for retaining said stub shafts in the inner ends of 60 said slots.

6. A device constructed in accordance with claim 5 wherein the means for retaining the stub shafts in the inner ends of said slots 65 comprises a member secured to said frame

and provided with a pair of resilient arms each contacting with one of the arms of said retaining member opposite the open end of the slot therein.

7. A device constructed in accordance 70 with claim 5 wherein the means for retaining the stub shafts in the inner ends of said slots comprises a member secured to said frame and provided with a pair of resilient arms each contacting with one of the arms of said 75 retaining member opposite the open end of the slot therein, said last named member being further provided with a pair of resilient arms each arranged adjacent the open end of the slot in one end of each arm of said 80 frame.

8. A safety razor comprising a frame having a pair of spaced upstanding arms adjacent its rear edge provided with alined rearwardly opening slots, a member arranged between said arms and provided with stub shafts projecting through said slots, a blade arranged on said frame, a retaining member normally arranged over said blade, said retaining member having upstanding arms arranged adjacent the arms of said frame and provided with forwardly opening slots receiving portions of said stub shafts, and a spring member secured to said frame and provided adjacent each end with a pair of 90 resilient arms, one resilient arm of each pair being arranged adjacent the open ends of the slots in the arms of said frame, the other of said resilient arms bearing against the arms of said retaining member rearwardly 95 thereof.

9. A device constructed in accordance with claim 8 wherein the member arranged between said arms comprises a roller, and means connected between said roller and said 105 blade for reciprocating the latter in a line parallel to its cutting edge when said roller is revolved.

10. A device constructed in accordance 110 with claim 8 wherein the member arranged between said arms includes a roller portion provided in its surface with a continuous serpentine groove, and operating means connected between said blade and said groove for reciprocating said blade in a line parallel to its cutting edge when said roller is 115 revolved.

11. A device constructed in accordance 120 with claim 8 wherein the member arranged between said arms includes a roller portion provided in its surface with a continuous serpentine groove, and a lever pivotally connected intermediate its ends to said frame and provided at one end with a portion arranged in said groove, the opposite end of said lever engaging a portion of said blade to reciprocate it in a line parallel to its cutting edge when said roller is revolved.

12. A safety razor comprising a frame, a retaining member arranged over said frame, 130

- the adjacent faces of said frame and said retaining member being provided with a plurality of projections extending beyond the faces of the frame and retaining member, a
- 5 blade arranged between said frame and said retaining member and resting upon the projections thereon, and means for reciprocating said blade in a line parallel to its cutting edge.
- 10 13. A device constructed in accordance with claim 12 provided with a pair of guide members arranged in a line parallel to the cutting edge of said blade, said blade being provided with slots to receive said guide members.
- 15 14. A safety razor comprising a frame provided at opposite ends of its forward edge with forwardly projecting arms, a blade arranged on said frame and having its cutting edge arranged adjacent the forward edge thereof, a cylindrical guard arranged parallel to the cutting edge of the blade and provided at one end with an eccentric pin arranged in the opening in one of said arms, the opposite end of said guard being provided with a threaded opening in alignment with said pin, and a screw mounted in the opening in the other of said arms and adapted to engage in the opening in said guard.
- 20 15. A safety razor comprising a frame
- provided at opposite ends of its forward edge with forwardly projecting arms provided with aligned openings, a blade arranged on said frame and having its cutting edge arranged adjacent the forward edge thereof, and a guard mounted between said arms, said guard having eccentric aligned projections at its ends arranged in said openings.
- 25 16. A safety razor comprising a frame provided at opposite ends of its forward edge with forwardly projecting arms provided with aligned openings, a blade arranged on said frame and having its cutting edge arranged adjacent the forward edge thereof, a cylindrical guard arranged parallel to the cutting edge of the blade and provided at one end with an eccentric pin arranged in the opening in one of said arms, the opposite end of said guard being provided with a threaded opening in alignment with said pin, and a screw mounted in the opening in the other of said arms and adapted to engage in the opening in said guard.

In testimony whereof I affix my signature.
JOHN L. KING.
